OUTDOOR GRILL

Richard W. Gier and Harrison Weaver, Jr., both
% Brillion Iron Works, Brillion, Wis.

Filed Aug. 18, 1961, Ser. No. 66,407

Term of patent 14 years

(Cl. D81—10)

The undisclosed side of the grill is a mirror image of the side shown in FIGURES 1 and 4.

We claim:
The ornamental design for an outdoor grill, substantially as shown and described.
